JOHN W. MACCLATCHIE, OF COMPTON, CALIFORNIA

REAMER

Application filed April 4, 1928. Serial No. 267,179.

This invention is a reamer particularly adapted for use in deep-well drilling and providing cutter elements projecting beyond the body of the tool for cutting engagement when the tool is rotated.

It is an object of the invention to employ suitable rollers as the cutting elements and to so journal the rollers in the tool as to prevent them wearing loose and wobbling.

10. The cutter rollers are preferably mounted in suitable bushings which are arranged in the body of the tool, and the invention provides for adjusting these bushings so as to compensate for all wear and thereby maintain proper relation of the parts.

It is another object of the invention to provide for ready replacement of all parts which are subject to wear, with washers which are mounted between the cutter rollers and the body of the tool, preferably included in said readily replaceable parts and so mounted as to be held against turning in order that wearing action will effect the replaceable washers rather than the body of the tool.

25. It is a further object of the invention to arrange the cutting elements so as to provide an initial tapering cutting engagement for properly guiding the reamer in the well bore and permitting movement thereof past obstructions and irregularities, and to then provide a substantially cylindrical cutting engagement for accurately reaming the well bore to true cylindrical form.

A still further object of the invention is 30. to arrange the cutting elements in series axially beyond one another, with the cutting elements of said series in circumferentially staggered relation so that a maximum circumferential cutting engagement is provided 40. without undue crowding of the next adjacent cutting elements of the same series.

It is a still further object of the invention to provide for proper circulation of a washing medium through the reamer, with a part 45. of the circulating fluid adapted for discharge in back of the cutting elements so as to avoid clogging of the tool and insure a flushing action immediately adjacent the points of cutting contact.

50. Further objects of the invention will be

readily understood from the following description of the accompanying drawings, in which:

Fig. 1 is a side elevation of the tool, partly in vertical section. 55

Fig. 2 is a fragmentary side elevation looking at the tool from a different angle as indicated by the line 2-2 of Fig. 3.

Fig. 3 is a transverse section on the line 3-3 of Fig. 1. 60

Fig. 4 is a perspective view of the supporting pin and associated parts for one of the cutter elements.

The invention is illustrated as embodied in a tool having a body 1 and a depending pilot end 2, with the body adapted for connection at its upper end to a usual string of drill pipe by means of the threaded pin 3, and the pilot end 2 preferably provided with a usual threaded box 4 for connecting a bit 70 or the like. 65

In the present embodiment of the invention the reamer is shown as provided with two series of cutting elements axially spaced one beyond the other, and the body 1 is provided with an elongated annular recess for each series of cutters, with said recesses 5 and 6 axially spaced by an annular enlargement 7 which preferably forms a continuation of the outer periphery of the body of the tool. 75

The peripheral bases of recesses 5 and 6 preferably form flat abutment surfaces 8 in back of the respective cutter elements, and in the present instance each recess is adapted to receive three cutter elements and the body of the tool is therefore triangular in cross-section at the recesses in order to provide a corresponding number of abutment surfaces. By limiting the number of cutter elements in each recess they may be equi-distantly circumferentially spaced without undue crowding, but in order to provide maximum circumferential cutting contact with the wall of a well bore the triangular cross-sectional areas of the tool at recesses 5 and 6 are preferably staggered with relation to one another as shown in Fig. 3, so that the cutter elements of the axially spaced series are in circumferentially staggered relation for insuring a substantially true cylindrical reaming action. 95 100

The cutter elements are shown as rollers 10 provided with usual cutter teeth 11, and these rollers are preferably journaled on axial pins 12 which are mounted in recesses 5 and 6 in spaced relation from the corresponding abutment surfaces 8 so that the cutter rollers are free to revolve with their peripheries projecting beyond the periphery of the body 1 for cutting engagement with the wall of a well bore.

The pins 12 are held in place by extending into bores provided in the overhanging shoulders which are formed by the medial enlargement 7 and the end enlargements 1^a and 1^b at the ends of recesses 5 and 6, and in order that the pins may be readily replaced they are adapted for convenient withdrawal and insertion by extending the bores 13^a for the upper ends of the pins of the respective series of cutter rollers so as to open through enlargement 7 and end enlargement 1^a respectively. An adjustable mounting is provided for the pin ends in their bores in order to compensate for wear, and as an instance of this arrangement the lower ends of the pins may be received in adjustable bushings 14 which are mounted in the corresponding bores 13^b for the lower ends of the pins, and the upper ends of the pins may form adjustable bushings 15 seating in the bores 13^a.

The bushings 14 and 15 may be adapted for radial adjustment in their corresponding bores by splitting the ends of the bushings as shown at 16 and forming the bushings of such resilient material as will permit of their ready radial expansion and contraction, and the bushings 14 may be expanded by providing the same with tapering bores 17 adapted for wedging reception of corresponding tapered ends 18 of the pins 12, while the bushings 15 are preferably expanded by tapered plugs 19 adapted for threaded reception in corresponding tapered bores 20 of the bushings.

By forcing the pins 12 downwardly into bushings 14 and threading the plugs 19 into bushings 15 the bushings may be expanded in their bores 13^b—13^a so that the pins 12 will be snugly held irrespective of wear of the parts. The cutter rollers 10 are thus adapted to revolve on their bearing pins without wobbling movement such as would otherwise result from the bearing pins working loose in their bores. To prevent wearing of the body of the tool by the ends of the revolving cutters, replaceable end thrust bearings are provided at the ends of the cutters, and in the present instance are shown as washers 25 mounted on pins 12 between the upper ends of the cutter rollers and the body of the tool, and washer heads 25^a which form integral parts of bushings 14 positioned at the lower ends of the cutter rollers. In order to prevent rotation of the washer elements and thereby maintain all wearing action at the replaceable washers rather than at the body of the tool, the washer

elements 25—25^a are preferably provided with flattened sides 26 adapted for abutment against the flattened surfaces 8 for holding the washers against turning.

The reamer is preferably arranged for initial tapering engagement with the wall of a well bore for properly alining the tool and moving the same past any obstruction, and is then adapted for cylindrical cutting engagement to insure the formation of a true cylindrical bore. For this purpose the pilot end 2 of the tool may include a taper 30 which preferably terminates at its upper end in a toothed peripheral surface 31 flaring outwardly slightly to form the periphery of body 1 at the base of lower recess 6, and the cutter rollers mounted in this lower recess are preferably angularly disposed so that their upper ends flare outwardly to define an annulus which substantially axially alines with the annulus defined by the rollers mounted in upper recess 5 and which preferably extend parallel to the axis of the tool.

The inclined toothed surface 31 of pilot 2 affords means for guiding the tool past any obstruction, with the inclined rollers in recess 6 then providing a tapering reaming action for cutting away any such obstruction so that the parallel rollers in recess 5 may ream the well bore to true cylindrical contour, and the staggered relation of the rollers in recesses 5 and 6 provides a maximum cutting surface without crowding the rollers in their recesses. In order to provide the desired angular disposition of the cutter rollers which are mounted in lower recess 6, the bores 13^a—13^b for the lower series of rollers are angularly arranged in the shoulders formed by medial enlargement 7 and the lower end enlargement 1^b, with the abutment surfaces at the ends of the recess 6 preferably disposed at right angles to the angular bores as shown in Fig. 2, so that washers 25—25^a will seat squarely on the abutment surfaces and present flat bearing surfaces for the revolving cutters.

The tool may be arranged for circulation of a washing medium by providing an axial bore 40 in the body 1 and opening through its ends for communication with the bore of drill pipe or the like from which the tool is suspended, and in order to insure a washing action immediately adjacent the points of cutting contact by rollers 10, lateral bores 41 preferably open from bore 40 into the recesses 5 and 6 in back of the cutter rollers so that the washing medium discharged therethrough will clear the rollers of cuttings and thereby avoid clogging action and will also provide a flushing action immediately at the points of cutting engagement by rollers 10. In order that the body of the tool shall not obstruct free circulation of the washing medium in the well bore, the end enlargements 1^a—1^b and the medial en-

largement 7 are preferably recessed between next adjacent cutter rollers as shown at 43.

The improved reamer thus provides for taking up all wear so as to prevent wabbling of the cutter elements and also provides for ready replacements and repairs. The construction also provides for initial tapering cutting engagement and subsequent parallel cutting action with the cutters adapted for maximum circumferential cutting contact without crowding of the parts. Furthermore the invention provides for circulating a washing medium without being obstructed by the body of the tool, and with the fluid so discharged as to free the cutters of foreign material and insure a flushing action immediately adjacent the points of cutting contact.

I claim:

1. In a reamer, a body having a bore, a bushing in the bore, a cutter assembly including and end supporting means mounted in said bushing, and means for radially adjusting the bushing so as to compensate for wear.

2. In a reamer, a body having axially spaced bores, a bushing in one of said bores, a pin having one end mounted in said bushing with its opposite end forming a bushing mounted in the other bore, a cutter mounted on the pin between said bores, and means for radially adjusting said bushings in the bores so as to compensate for wear.

3. In a reamer, a body having a bore, a cutter element having an end supporting means mounted in said bore and forming a split bushing, and means for radially adjusting said bushing in the bore.

4. In a reamer, a body having a bore, a split bushing in said bore having a tapering bore, and a cutter assembly including a tapering end supporting means adapted for wedging reception in the bore of the bushing for expanding the bushing in the bore of the body.

5. In a reamer, a body having a bore, a bushing in the bore having an end forming a thrust washer, a pin mounted in the bushing, a cutter rotatably mounted on the pin and abutting against the thrust washer, and means for radially adjusting the bushing so as to compensate for wear.

6. In a reamer, a body having a bore, an axially split bushing in the bore, and a cutter assembly including an end supporting means adapted for reception in the bore of the bushing.

7. In a reamer, a body having axially spaced bores, a bushing in one of said bores, a cutter assembly including end supporting means, one of the end supporting means being mounted in the bushing with the opposite end supporting means mounted in the other bore, and means for radially adjust-

ing the bushing so as to compensate for wear.

8. In a reamer, a body having axially spaced bores, a split bushing in one of said bores, said bushing having a tapering bore, and a cutter assembly including end supporting means, one of the end supporting means being adapted for wedging reception in the bore of the bushing with the opposite end supporting means mounted in the other bore of the body.

9. In a reamer, a body having axially spaced bores, a bushing in one of said bores, a cutter assembly including end supporting means, one of the end supporting means being mounted in the bushing, the opposite end supporting means forming a bushing adapted for mounting in the other bore, and means for radially adjusting the bushings so as to compensate for wear.

10. In a reamer, a body having axially spaced bores, a split bushing in one of said bores, said bushing having a tapering bore, a cutter assembly including end supporting means, one of the end supporting means being adapted for wedging reception in the bore of the bushing, the opposite end supporting means forming a bushing adapted for mounting the other bore of the body, and means for radially adjusting the last mentioned bushing so as to compensate for wear.

In testimony whereof he has affixed his signature to this specification.

JOHN W. MACCLATCHIE.
